UNITED STATES PATENT OFFICE.

JESSE G. HENDERSON, OF GRIZZLY FLAT, CALIFORNIA.

TRUSS.

SPECIFICATION forming part of Letters Patent No. 349,498, dated September 21, 1886.

Application filed May 27, 1886. Serial No. 203,477. (No model.)

To all whom it may concern:

Be it known that I, JESSE G. HENDERSON, of Grizzly Flat, county of El Dorado and State of California, have invented an Improvement 5 in Trusses; and I hereby declare the following to be a full, clear, and exact description thereof.

My invention relates to the class of trusses for the alleviation or cure of hernia; and my 10 invention consists in the construction and combination of devices, all of which I shall hereinafter fully describe.

The object of my invention is to provide a simple and effective truss—one which can be 15 worn without inconvenience, and which on the contrary will give the wearer all the comfort to be obtained from a perfectly-fitting, pliable apparatus, the pad of which is soft and yielding, and on account of its construction and the 20 connection of the securing-bands, cannot get out of place, but will remain in position no matter what may be the positions assumed by the wearer.

Referring to the accompanying drawings, 25 Figure 1 is a perspective view of my truss. Fig. 2 is a side elevation of the pad.

A A are the securing straps or bands. B is the pad. This is made of spring-wire coiled spirally to the shape of a cone-frustum. Its 30 smaller end is entirely open, as at b, and that coil b' which forms the small end is smoothed down to a flat surface, as shown, its end being beveled off and properly secured or welded, so that the whole surface is flush and flat. 35 The other end or base of the pad is also open, and the end of the wire is looped around the adjacent coil, thus forming a perfect whole. The bands A are secured upon the base coil by being looped thereon and sewed, so that 40 they may slip, and thus adjust themselves without drawing upon the wire. The bands are provided with suitable buckles or other fastenings, by which they may be secured in place.

45 In using the truss the small open flat end of

the wire pad comes in contact with the skin, and presses just over the point of rupture. The end being flat prevents discomfort, while by being open it cannot get out of position, for the skin and flesh being pressed rise up 50 in the open end and afford a bearing, so to speak, for holding the pad. The soft yielding character of the spring prevents undue pressure, though it is still firm enough to effect the object intended, at the same time providing 55 for the motions of the body. It smooths out the rupture instead of pressing against it solidly, and when sufficiently pressed all the coils come down flat and cover the whole rupture. It can be worn night as well as day, the slipping of the bands A preventing any tendency 60 to draw the pad from its place.

For a double truss a pad may be placed on each side, or a single truss may be reversed. There is no covering to go over the spring- 65 wire pad.

I am aware that a pad has been invented, made of spring-wire coiled; but its shape is not like mine, being an oval or double cone, small at both ends and neither end open, which 70 makes it rather unstable and difficult to adjust. I do not therefore claim, broadly, a coiled-spring-wire pad, but confine myself to the particular pad I have described.

Having thus described my invention, what 75 I claim as new, and desire to secure by Letters Patent, is—

A truss comprising the pad B, made of spring-wire coiled spirally to the shape of a cone-frustum, its smaller or contact end being open and having a flat smooth surface, and the securing-bands A, secured to the base-coil of the pad, substantially as herein described.

In witness whereof I have hereunto set my 85 hand.

J. G. HENDERSON.
